CLAIM

The ornamental design for display screen with animated graphical user interface, as shown and described.

DESCRIPTION

FIG. 1 is a first image in a non-sequential order for a display screen with animated graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the image transitions sequentially between the images shown in FIGS. 1 through 7 by touching the images on the screen. The process or period in which one image transitions to another forms no part of the claimed design.

The outermost broken line showing a display screen forms no part of the claimed design. The remaining broken lines, showing portions of the display screen and portions of the graphical user interface, form no part of the claimed design.
